UNITED STATES PATENT OFFICE.

ALCADA F. DODSON, OF MILAN, MISSOURI.

CALCULATING-MACHINE.

1,336,686.

Specification of Letters Patent. Patented Apr. 13, 1920.

Application filed February 4, 1918. Serial No. 215,354.

To all whom it may concern:

Be it known that I, ALCADA F. DODSON, a citizen of the United States, residing at Milan, in the county of Sullivan and State 5 of Missouri, have invented certain new and useful Improvements in Calculating-Machines, of which the following is a specification.

My invention relates to improvements in 10 calculating machines, adapted for use in determining the cost of a selected number of yards or units of goods, at a given price.

An important object of the invention is 15 to provide a machine of the above mentioned character, which is highly convenient and expeditious in use.

A further object of the invention is to 20 improve the construction in general, providing a machine which is reliable in operation and not liable to derangements.

Other objects and advantages of the invention will be apparent during the course 25 of the following description.

In the accompanying drawings forming a part of this specification and in which like numerals are employed to designate like parts throughout the same,

Figure 1 is a plan view of apparatus embodying my invention,

Fig. 2 is a side elevation of the same,

Fig. 3 is a central longitudinal sectional view through the apparatus, parts being shown in elevation,

Fig. 4 is a transverse sectional view taken 35 on line 4—4 of Fig. 3,

Fig. 5 is a similar view taken on line 5—5 of Fig. 6,

Fig. 6 is a central vertical longitudinal sectional view taken on line 6—6 of Fig. 4,

Fig. 7 is a transverse sectional view taken 40 on line 7—7 of Fig. 6,

Fig. 8 is a similar view taken on line 8—8 of Fig. 6,

Fig. 9 is a transverse sectional view taken 45 on line 9—9 of Fig. 12a,

Fig. 10 is a side elevation of the control plate shifting means,

Fig. 11 is a transverse sectional view taken on line 11—11 of Fig. 12,

Fig. 12 is a longitudinal section taken 50 on line 12—12 of Fig. 11,

Fig. 12a is a fragmentary plan view of the apparatus, and,

Fig. 13 is a fragmentary side elevation 55 of the chart.

In the drawings, wherein for the purpose

of illustration is shown a preferred embodiment of my invention, the numeral 15 designates a casing, which is preferably formed of sheet metal. This casing is substantially 60 U-shaped in cross-section and its upper surface or face is preferably flat. As more clearly shown in Figs. 1 and 12a, the flat face or top of the casing 15 is provided with a longitudinal opening 16, spanned by a section of glass 17, or other transparent material. This glass is held in place by flanges 18, as clearly shown in Figs. 7 and 9. Formed upon the top of the casing 15 and extending longitudinally along the opening 70 16 is a scale 19, preferably representing a unit of measure, in this particular instance a yard. This scale is divided into inches, as shown. Arranged inwardly of and near the yard scale 19 is a scale or chart 20, designating the price of the goods to be measured, per unit or yard. A correspondingly arranged scale 21 is disposed upon the opposite side of the opening 16, and designates the price of the goods in smaller units, 75 such as one-eighth of a yard.

As clearly shown in Fig. 12a, a window 22 is secured to the top of the casing 15 and has an opening 23. Within this opening are "Price per yard" indicating the character of 80 the scale 20 and "Price per $\frac{1}{8}$ yard" indicating the character of the scale 21. Within the opening 23 can also be seen that portion of a chart, to be described, indicating the number of yards which have been measured.

Attached to one end of the casing 15 is a flanged cap 22' to which is secured a frame-plate 23', shown more clearly in Figs. 4, 5 and 6. The frame-plate carries posts 24, 95 rigidly secured thereto, and a coacting frame-plate 25 is secured to the opposite ends of the posts 24.

As more clearly shown in Fig. 6, a driving shaft, 27 is journaled through openings 100 28. This driving shaft has a rotatable element 29 rigidly secured thereto. Outwardly of the rotatable element 29 the driving shaft is provided with a screw-threaded portion 30, having screw-threaded engagement with the head 31 of a depending stop 32, to be described. The driving shaft 27 extends through openings 33 and 34, and is provided exteriorly of the casing 25' with a hand wheel 36, rigidly secured thereto. The 105 rotatable element 29 embodies an inner ratchet wheel 37, having its teeth facing

- counter-clockwise, as more clearly shown in Fig. 5. This rotatable element also comprises an outer ratchet wheel 38, having its teeth facing counter-clockwise. A plate 39 is interposed between the two ratchet wheels 37 and 38, and has an opening to receive a portion of the rotatable element 29 but without interfering with the rotation thereof.
- 10 Means are provided to rotate the driving shaft 27 clockwise, comprising an inner reciprocatory element or bar 40, contacting with the inner side of the frame-plate 23. This inner reciprocatory element or bar is free to move vertically but cannot partake of perceptible lateral movements. The numeral 43 designates an outer reciprocatory element or bar, arranged to contact with the inner side of the inner element or bar 40 and having diagonally arranged slots 44, receiving lugs 45, which are rigidly attached to the bar 40. It is thus apparent that upon the downward movement of the bar 43 the same will first move laterally and downwardly with respect to the bar 40 and when the lugs 45 contact with the upper ends of the slots 44, the two bars 40 and 43 will move downwardly together. When the bar 43 is shifted laterally, as above indicated, 25 teeth 46 formed upon one edge thereof are brought into contact with the ratchet wheel 37, whereby upon further downward movement of the bar 43 this ratchet wheel is turned for the proper distance. At its lower 30 end the bar 43 is provided with a lateral extension 47, having connection with a retractile coil spring 48, having its upper end attached to the stationary element 49 and serving to move the bar 43 upwardly.
- 35 40 As more clearly shown in Fig. 5, the bar 40 is provided at its lower end with a shoulder 50, adapted to be engaged by a dog 51, pivoted at 52. This dog is moved to the active position by means of a spring 53. The 45 lower end of the bar 43 is provided with a cam element 54, which when the bar 43 is moved downwardly for a slight distance and shifted laterally, contacts with the upper end of the dog 51, thereby moving the same 50 from beneath the shoulder 50, and releasing the bar 40 for downward movement.
- 55 As more clearly shown in Figs. 4 and 5, a swinging lever 55 is provided, which is U-shaped in cross-section, for the reception 60 of the upper end of the bar 43. This upper end is beveled, as shown at 56, for contact with a transverse element 57, attached to the lever 55. The opposite end of the lever 55 straddles a stationary support or bracket 58, attached to a top plate 59, and is pivoted thereto, as shown at 60.
- 65 The backward turning movement of the operating shaft 27 is normally prevented by means of a pawl 61, arranged to engage the ratchet wheel 38. This pawl is pivoted at 62 and is provided with a lever portion 63. At one end, this lever portion carries a button 64, arranged in an opening 65. The opposite end of the lever portion 63 is provided with a flange 66, having connection 70 with a retractile coil spring 67, attached to one of the posts 24. When the button 64 is pressed inwardly the pawl 61 is moved out of engagement with the ratchet wheel 38.
- 75 The rotatable element 29 is provided outwardly of the ratchet wheel 38 with a brake drum 69, adapted to be engaged by a brake shoe 70, carried by a reciprocatory rod 71. This reciprocatory rod has its lower portion operating within a stationary apertured 80 bracket 72 while its upper portion extends through a slot in the flange 66. A compressible coil spring 73 is arranged between the flange 66 and the brake shoe 70. When the button 64 is pushed inwardly to move 85 the pawl 61 out of engagement with the ratchet wheel 38, the flange 66 will place the spring 73 under tension, thereby shifting the brakeshoe 70 into contact with the drum portion 69, for preventing the operating shaft 27 from rotating in a reverse direction at too high a speed.
- 90 The stop element 32 is arranged within a slot 74 of a stationary element or bracket 75, and therefore cannot rotate, but is 95 adapted to travel longitudinally of the screw-threaded portion 30. When the driving shaft 27 is rotated in an opposite direction or counter-clockwise, the stop element 32 travels toward a disk 76, formed upon 100 the rotatable element 29 and this stop element will be engaged by a tooth 77, formed upon the disk 76, whereby further rotation of the shaft 28 is positively prevented. In other words, means are provided to prevent 105 the rotation of the operating shaft 27 beyond a predetermined number of revolutions.
- 110 Secured to the opposite end of the casing 15 is a plate 78, having a frame-plate 79, rigidly secured thereto, as shown at 80. Spaced from the frame-plate 79 is an inner plate 81 secured thereto by means of posts 82. As more clearly shown in Fig. 12, a shaft 83 has its inner end thereof rotatable 115 within an opening 84 in the plate 81, and a ring 85 is rigidly secured to the shaft outwardly of the plate 81. Arranged upon the shaft 83 is a sleeve 86. The outer end of the shaft 83 is screw-threaded for the reception of a clamping nut or cap 87 having screw-threaded engagement therewith. Surrounding the sleeve 86 is a spiral spring 88, one end of which is attached to the sleeve 86, and the opposite end of which is secured 125 to one of the posts 82, as shown at 89 in Fig. 3. Arranged upon the shaft 83 is a large gear 90 disposed between the ring 85 and the inner end of the sleeve 86. When the nut 87 is screwed up, the sleeve 86 clamps 130

the gear 90 to the flange 85, whereby parts 83, 85, 90, 86 and 87 all may be rotated together, as a unit. The gear 90 engages a smaller gear 91, rigidly attached to a stub-shaft 92, rotatable in the frame-plate 81. It is thus apparent that the spring 88 is adapted to rotate the gear 91 in a counter-clockwise direction, when the stub-shaft is released.

Arranged within the casing 15 and extending longitudinally thereof in parallel relation is an upper winding roll 93 and a lower take-up roll 94. As more clearly shown in Fig. 6, the shaft 27 has a plug or member 95 rigidly secured thereto, which projects into one end of the tubular roll 93, which is clamped to the plug by means of a clamp 96 or other device, whereby the upper roll turns with the plug. At its opposite end, the upper roll 93 is suitably connected with a stub-shaft 97, rotatable in the frame-plate 81. The lower tubular roll 94 has suitable connection with a stub-shaft 98, see Fig. 6, which is rotatable in an opening 99, in the cap 22'. At its opposite end the lower roll 94 is rigidly connected with the stub-shaft 92.

Suitably connected with the upper roll 93 is a flexible chart 100, provided with vertical and horizontal lines 101 and 102, providing spaces for the reception of calculations 103, adapted to be arranged in coöperative relation to the scale 20. Centrally of the chart 100 is a column 103', indicating the number of yards or fractions thereof, which have been measured and designated "No. yards." This column of figures is apparent within the opening 16 through the opening 23 of the window 22.

Control means are provided for regulating the extent of turning movement of the driving shaft 27, upon each stroke of the lever 55, comprising a reciprocatory or movable control element or plate 104, shown more clearly in Figs. 3 and 10. This control plate is provided upon its upper portion with a plurality of steps 105, 106, 107, 108, and 109. The control plate 104 is pivoted at its lower end, as shown at 110, with a stationary plate 111. The control plate 104 is moved to the left in Fig. 3, by a retractile coil spring 112, attached thereto, and to one of the posts 24. When in the normal position, the uppermost shoulder 105 engages beneath a tooth or lug 113, preferably formed integral with the reciprocatory bar 40, thereby positively limiting the downward movement of the bar 40.

As more clearly shown in Figs. 3 and 10, a reciprocatory rod 114 is pivoted to the reciprocatory control member 104, at 115. This reciprocatory rod extends longitudinally within the casing 15 and is guided by apertured brackets 116, formed upon stationary plates 117. The rod 114 has a plu-

rality of collars 118, rigidly secured thereto and adapted to contact with the apertured brackets 116 when the rod 114 is moved to the end of its travel in the direction of the arrow. Pivoted to the stationary plates 117 as shown at 119, 120, 121, and 122, are bell-crank levers 123, 124, 125, and 126, respectively. The lower ends of the vertical arms of these levers are adapted to contact with the collars 118. The bell-crank lever 123 is so constructed and pivoted that when it is moved downwardly for the entire extent of its travel it will shift the control plate 104 to the right in Fig. 3, sufficiently whereby the lug 113 will be positioned above the second shoulder 106; the bell-crank lever 124 will shift the rod 114 sufficient to move the plate 104 so that the lug 113 will contact with the shoulder 107; the bell-crank lever 125 will shift the plate 104 sufficiently to cause the lug 113 to contact with the shoulder 108; and the bell-crank lever 126 will move the plate 104 sufficiently to cause the lug 113 to contact with the shoulder 109. The bell-crank levers are actuated by reciprocatory pins or plungers 127, 128, 129, and 130 respectively. Each pin has the upper portion thereof mounted within an aperture formed in a stationary ear 131 and the lower end of the pin is reduced to form an extension 132 and a shoulder 133. The reduced extension 132 operates within an aperture formed in a stationary ear 134. A shoulder or ring 135 is rigidly secured to each pin 127 and is disposed above the horizontal arm of the bell-crank lever.

As more clearly shown in Fig. 1, the pins extend through openings formed in the top of the casing section, and the pin 127 is located at the nine inch point on the yard scale 19, and is thereby adapted to measure a $\frac{1}{4}$ yard. The pin 128 is located at the eighteen inch point on the yard scale 19 and is therefore adapted to measure $\frac{1}{2}$ of a yard. The pin 129 is located at the twenty-seven inch point on the yard scale and is therefore adapted to measure $\frac{3}{4}$ of a yard and the pin 130 is located at the thirty-six inch point and is therefore adapted to measure a yard.

In use, the casing 15 is preferably arranged upon the inner side of the shop counter with its top thereof flush with the counter. The casing may be secured to the counter by brackets or any other suitable means. As an illustration of the operation of the apparatus, it may be assumed that it is desired to sell $5\frac{1}{2}$ yards of cloth at 50c per yard and to ascertain the correct total amount of the sale. The bolt of cloth is arranged upon the counter to the right of the machine and the operator holds the free end of the cloth in the left hand and brings same in proximity to the scale 19 to measure a yard, holding the cloth upon the two ends 130

of the yard scale 19 by the hands. While in this position, the operator depresses the pin 130 with the left hand while holding the cloth and retains this pin depressed while the lever 55 is forced downwardly with the right hand while the cloth is being held thereby. This downward movement of the lever 55 first causes the plate 43 to move slightly downwardly and laterally whereby its cam 54 shifts the dog 51 from beneath the shoulder 50. The continued movement of the bar 43 downwardly causes the bar 40 to move with it. The bar 40 will move downwardly until the lug 113 thereof contacts with the shoulder 109. This operation is repeated until five yards of cloth are measured. To measure the half of a yard the goods is placed upon the yard scale 19 and the pin 128 is depressed, and the lever 55 is depressed. The bar 40 will not move down for its entire extent of travel but its downward movement is stopped when the lug 113 contacts with the shoulder 107. The operator now turns to the scale 20, and to the "50" designation. Beneath this designation, in the opening 16, and upon the chart 101 will be found \$2.75, the total amount.

When it is desired to rewind the chart, preparatory to a new operation, the operator forces the button 64 inwardly whereby the pawl 61 disengages the ratchet wheel 38 and the spring 88 and associated elements turn the take-up roll 94 counter-clockwise, thereby restoring the parts to the normal position. The movement of the upper roll 93 is positively limited, when the chart is returned to the proper normal position by the stop 32 traveling to the right, in Fig. 6, and into the path of travel of the tooth 77, which engages therewith.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I

claim:

1. In a machine of the character described, a support, an indicia carrying device connected therewith, a driving shaft connected with the device, a toothed wheel rigidly secured to the driving shaft, a reciprocating bar, a coacting reciprocating bar extending longitudinally of the first named bar, connecting means between the first and second named bar whereby the second named bar is shifted laterally with respect to the first named bar upon the longitudinal movement of the second named bar in one direction, means carried by the second named bar to engage the toothed wheel to advance the same, and means to

longitudinally move the second named bar in one direction.

2. In a machine of the character described, a support, an indicia carrying device connected therewith, a toothed wheel connected with the device to operate the same, a movable bar, a coacting movable bar extending longitudinally of the first named bar, connecting means between the first named bar and second named bar whereby the second named bar is shifted laterally with respect to the first named bar upon the longitudinal movement of the second named bar in one direction, yielding means to oppose the longitudinal movement of the second named bar in one direction, lock means to hold the first named bar against longitudinal movement in one direction and adapted to release the same upon the lateral movement of the second named bar, and means carried by the second named bar to engage the toothed wheel and advance the same.

3. In a machine of the character described, a support, an indicia carrying device connected therewith, a toothed wheel connected with the device, a bar adapted to reciprocate longitudinally and incapable of partaking of perceptible lateral movement, a coacting longitudinally and laterally movable bar disposed upon one side of the first named bar and provided with inclined openings, stationary elements operating within the inclined openings and secured to the first named bar, means carried by the second named bar to engage the toothed wheel and advance the same, yielding means to oppose the longitudinal movement of the second named bar in one direction, and a dog adapted to engage the first named bar to normally hold the same against longitudinal movement in one direction and disposed to be shifted to the inactive position by the second named bar.

4. In a machine of the character described, a rotatable member, a support with which the member is connected, a gear secured to the member to drive it, a shaft pivotally connected with the support and provided with a flange, a second gear having an opening to receive the shaft and engaging the first named gear, a sleeve carried by the shaft and adapted to contact with the second named gear, a clamping nut having screw-threaded engagement with the shaft and engaging the sleeve, and a spring surrounding the sleeve with one end thereof connected therewith and the opposite end of the spring being connected with the support.

5. In a machine of the character described, an indicia carrying device, a toothed wheel connected with the device to drive the same in one direction, a longitudinally and laterally movable member having means to

- engage the toothed wheel to advance the same and normally spaced from the toothed wheel, a coacting longitudinally movable member having means engaging the first-named member to effect the lateral movement thereof when the first-named member is moved longitudinally in one direction with relation to the second-named member, and means to normally hold the second-named member against longitudinal movement in one direction and adapted to be shifted by the first-named member to release the second-named member so that it is free to move longitudinally with the first-named member.
- 6 10 14 18 22 26 30
- 15 6. In a machine of the character described, a support having a scale extending longitudinally thereof, said scale being divided into a plurality of selected units; an indicia carrying device; a manually operated element to advance the device for selected distances; a pivoted control member
- having means to limit the movement of the manually operated element and to cause the same to operate the device for different distances; a plurality of vertically movable depression pins arranged in proximity to the scale and serving to divide the same into a 25 plurality of selected units; a common reciprocatory rod pivotally connected with the pivoted control member and carrying a plurality of collars; and a plurality of pivoted bell crank levers arranged to engage the 30 collars and adapted to shift the rod for different distances, said bell crank levers being actuated by the vertically movable depression pins.
- 35 In testimony whereof I affix my signature in presence of two witnesses.
